UNITED STATES PATENT OFFICE

PAUL CRICCHIO, OF NEW YORK, N. Y., ASSIGNOR TO MAJESTIC LAMP WORKS, OF NEW YORK, N. Y., A PARTNERSHIP CONSISTING OF PHILIP SILBERHARTZ, JACOB SILBERHARTZ, AND HARRY SCHEINER, ALL OF BROOKLYN, NEW YORK

DESIGN FOR A COMBINED CLOCK CASE AND LAMP

Application filed April 11, 1930. Serial No. 35,211. Term of patent 3½ years.

To all whom it may concern:

Be it known that I, PAUL CRICCHIO, a citizen of the United States, and a resident of New York, county of Bronx, and State of New York, have invented a new, original, and ornamental Design for a Combined Clock Case and Lamp, of which the following is a specification, reference being had to the drawing, forming a part thereof.

I claim:

The ornamental design for a combined clock case and lamp substantially as shown.

PAUL CRICCHIO.
